WHEEL

Roy E. Richter, 9835 Wileyburke Ave.,
Downey, Calif. 90240

Filed Sept. 21, 1970, Ser. No. 25,084

Term of patent 14 years

Int. Cl. D12—16

U.S. Cl. D14—30

FIG. 1 is a front elevational view of the wheel embodying my new design;

FIG. 2 is a rear elevation;

FIG. 3 is a cross-section on the line 3—3 of FIG. 2; and

FIG. 4 is a perspective view.

This design is characterized by the conical nature of the spider within or inboard of the five slots. This conical face, as it passes over the five lug holes, creates a distinctive elliptical shape at each lug hole, which blends into the center hub at the inward termination of the cone.

I claim:

The ornamental design for a wheel, substantially as shown and described.
